UNITED STATES PATENT OFFICE

2,616,395

INKSTAND AND PENHOLDER

Leon H. Ashmore, Atlanta, Ga., assignor to
 Scripto, Inc., Atlanta, Ga., a corporation of
 Georgia

Application February 14, 1947, Serial No. 728,509

2 Claims. (Cl. 120—71)

1

The invention relates to pen holders for use with the usual fountain ink well to provide an assembly commonly referred to as desk set.

It is an object of the invention to provide a pen holder that will reduce or prevent the access of ink to the portion of the pen holder which is grasped by the user.

It is a further object of the invention to provide a pen holder and ink well having means to insure that the holder will always be placed in the ink well in a certain position.

Further objects will appear from the following description when read in connection with the accompanying drawing showing an illustrative embodiment of the invention and wherein:

Figure 1 is a side elevation partly in section of an ink well and pen holder;

Figure 2 is a detail side elevation of a portion of the holder shown in Figure 1 drawn to an enlarged scale;

Figure 3 is a vertical transverse section on line 3—3 of Figure 2;

Figure 4 is a detail plan view of a holder-receiving element; and

Figure 5 is a section on line 5—5 of Figure 4.

As shown, a fountain ink well of a form commonly in use is provided with the structure of the present invention. The opening into the ink well is shown as provided about its margin with a ridge 11 and the opening is inwardly tapered. As will be evident from viewing Fig. 1, the mouth of the opening which extends into the ink well lies in a plane which extends transversely of said opening. In fact, the plane in which the ink well mouth lies is substantially at right angles to the longitudinal axis of the ink well opening. Fitting within the opening and overlying the ridge 11, there is shown a thin bushing 12 which forms a lining for the ink well opening and which has a flange formed to fit the eminence 11. The bushing 12 has one of its walls flattened as shown at 13 in Figure 4. To retain the bushing 12 in the opening, the lower margin of the bushing is shown as flared outwardly to engage the wall of the opening. The pen holder 14 is shown as having an end 15 to fit in the bushing 12 and as formed with a flattened portion 16 to correspond with the portion 13 of the bushing. The end 17 of the pen holder as shown in Figures 2 and 3 is formed at an angle to the axis of the holder and the end surface is made flat as indicated at 18 in Figure 2. As will be evident from viewing Figs. 1 and 2, the end face 18 of the pen nib receiving portion 15 of pen holder 14 has a peripheral edge which lies in a plane which is inclined with re-

2

spect to the plane in which the mouth of the ink well opening lies. As is explained in further detail below, this arrangement enables the ink film at the mouth of the ink well opening to be broken progressively when the pen nib receiving portion 15 is withdrawn from the ink well opening.

The pen holder is also shown as formed with a chamber 19 for reception of the usual feed bar 20. The location of the holder in the opening in the ink well by means of the registration of the flattened portions 13 and 16 will cause the feed bar 20 and the nib 21 to always be in the same position whereby to receive at all times a uniform quantity of ink. When the holder is removed from the bushing 12 any film of ink upon the end 15 of the holder will be broken and the groove shown at 22 between 15 and 24 on the end of the holder serves to prevent the creeping of ink upwardly along the pen holder to the portion grasped by the fingers. It is obvious from Figs. 1 and 2 that the spaced apart ridges 23 and 24 are positioned substantially immediately above the flattened portion 16 of pen nib receiving portion 15 and that the groove 22 defined by these ridges extends circumferentially about the pen holder.

An important result of ensuring that the pen holder shall always be inserted in the relation to the ink well shown, is that the same amount of ink will always be taken by the nib and feed bar. A film of ink almost inescapably becomes deposited on the opening of the well. When the pen holder is withdrawn, surface tension of the ink, broken completely around the end of the holder, which is perpendicular to the axis of the holder, leaves a substantial amount of ink on the holder. To avoid this it is customary to wipe the holder against the periphery of the opening.

The angle of the end surface 18 of the pen holder, to the axis of the holder has the function of breaking the surface tension of the film of ink at one point in advance of the remainder of the periphery, when the holder is withdrawn for use thus considerably lessening the amount of ink carried by the pen holder. In fact, much the same effect is secured by mere withdrawal of the pen holder, as is secured by the above-described wiping.

Minor changes may be made in the physical embodiments of the invention within the scope of the appended claims without departing from the spirit of the invention.

I claim:

1. An ink well and pen holder combination

comprising an ink well having a generally circular pen holder receiving opening therein, said opening having a mouth lying in a plane extending transversely of said opening, a bushing lining said opening and extending lengthwise thereof, said bushing having a flange thereon which engages the ink well at said opening to retain the bushing substantially immovably in place and said bushing also having a flattened wall portion extending lengthwise of said opening, and a pen holder having a pen nib receiving end portion, including a flattened surface, shaped complementary to the shape of said bushing whereby said pen holder may be seated against said bushing and within said ink well opening in one circumferential position only, said pen nib receiving portion having an end face bounded by a peripheral edge lying in a plane which is inclined with respect to the plane in which the mouth of said ink well opening lies whereby, when said pen nib receiving portion is withdrawn from said opening, any ink film at said opening is broken progressively thereby substantially lessening the amount of ink remaining on the surface of said pen nib receiving portion after it is withdrawn from the ink well opening.

2. An ink well and pen holder combination comprising an ink well having a generally circular pen holder receiving opening therein, said opening having a mouth lying in a plane extending transversely of said opening, a bushing lining said opening and extending lengthwise thereof, said bushing having a flange thereon which engages the ink well at said opening to retain the bushing substantially immovably in place and said bushing also having a flattened wall portion extending lengthwise of said opening, and a pen holder having a pen nib receiving end portion, including a flattened surface, shaped complementary to the shape of said bushing whereby said pen holder may be seated against said bush-

ing and within said ink well opening in one circumferential position only, said pen nib receiving portion having an end face bounded by a peripheral edge lying in a plane which is inclined with respect to the plane in which the mouth of said ink well opening lies whereby, when said pen nib receiving portion is withdrawn from said opening, any ink film at said opening is broken progressively thereby substantially lessening the amount of ink remaining on the surface of said pen nib receiving portion after it is withdrawn from the ink well opening, and a pair of spaced apart ridges on said pen holder, said ridges being located substantially immediately above the flattened surface on the pen nib receiving portion and defining a groove which extends circumferentially about said pen holder, said groove serving to prevent creeping of ink to the portion of the pen holder grasped by the user.
